LEAKAGE INDICATING DEVICE FOR GAS-FILLED ELECTRIC CABLES, PIPE LINES, OR THE LIKE

Edward Leslie Davey, Hale, England, assignor to
W. T. Glover & Company Limited, Trafford
Park, England, a British company

Application January 4, 1947, Serial No. 720,278
In Great Britain January 17, 1946

4 Claims. (Cl. 73—40.5)

1

In an electric cable system which is intended to remain filled with gas at a pressure different from that of the external atmosphere, it is important to have some means of detecting a leak and finding the position of it. This means can be provided if the system is sectionalised, since an agreement can then be set up for obtaining an indication of any pressure difference arising between adjacent sections. Permanent sectionalising, however, makes difficult the filling of the system, either initially or when required after installation.

The present invention resides in the incorporation in a sectionalized gas-filled electric cable system of a device which, while capable of forming a cut-off between sections and indicating small differences of pressure on opposite sides of the cut-off, also permits ready flow of gas between the sections when a substantially larger pressure difference exists, such as is established during filling of the system with gas.

The device is a pressure relief manometer which comprises a large bore U-tube which is inserted in a by-pass connected across a barrier between two sections of the system and is under normal operating and leak conditions, closed by mercury in the tube. The term "large bore" is used herein, to mean a bore that is sufficiently large for the mercury column therein to be readily broken up to permit gas to bubble through it when there is a large pressure difference between the sections such as exists during the filling of the system. This large bore U-tube is adapted to indicate a displacement from normal of the mercury level due to a small difference in the pressure across the barrier occasioned by a leakage of gas from a neighbouring section of the system and is designed to prevent or has means for preventing the carry-over of mercury into parts of the system external to it when gas is bubbling through the mercury. The barrier across which the U-tube is connected constitutes a more or less complete closure for the main gas space. Such a barrier may, for instance, be provided at a point in an electric cable by the wrappings of insulating material which are applied over the conductor joint and over the adjacent insulating material of the cable ends. The pressure difference across the cut-off formed by the mercury in the U-tube when a leak is taking place in a section at one side of the barrier is very much less than is applied when the system is being filled with gas. The latter may, for instance, be from 15 to 20 times the former. Thus the device provides an inappreciable obstacle to the flow of gas during

2

the process of filling the system with gas under pressure, while it serves as a complete seal and a sensitive detecting device for leakage conditions. In the latter state the displacement of the mercury level may only be of the order of $\frac{1}{8}$ inch, whereas under the former conditions there is more or less violent bubbling through of the gas with the throwing of the mercury up one of the legs of the U-tube.

In order to prevent carry-over of mercury out of the U-tube into the external system when gas is bubbling through the mercury, a U-tube with much elongated legs could be used. This, however, would generally be inconvenient, and in general I prefer to provide a porous barrier at each side of the U-tube, which will readily permit the passage of gas under the pressures existing, but will not permit the passage of mercury under the maximum pressure difference which can occur. Each barrier is preferably in a chamber connected to a side branch from a part of the U-tube leg below the top thereof. This permits the mercury which is thrown upward by the passage of the air to fly past the opening of the branch to the upper part of the U-tube leg which is closed off. The branch preferably slopes upwards from the U-tube so that any globules of mercury which enter it will pass back again to the U-tube. The porous barrier is preferably of a larger diameter than the bore of the U-tube so as to give an extended surface for the passage of gas. A suitable barrier is provided by a plate of sintered glass which has the additional advantage that it can be fused integral with the wall of the chamber in which it is closed. This may be a short cylinder with a disc of sintered glass across the centre of it and with a short connecting tube at each end, that tube which is for connection to the branch from the U-tube, being at one side of the end of the cylinder, namely the lower side when in position. This also facilitates the running back of any mercury which is carried over into the branch and into the chamber on it. The U-tube with its branches is also preferably made of glass.

The indication of an unbalance of the mercury levels in the legs of the U-tube due to the existence of a leak may be obtained by direct observation of the tube, where that is convenient, but it is usually preferable and advantageous to provide for an indication of a small out of balance by the closing of electric contacts by means of the rising surface of mercury. This can readily be provided for by arranging in each leg of the U-tube a pair of contact wires with their ends a

short distance above the normal balanced position of the mercury surface. These wires may pass through and be fused into the glass walls of the legs of the U-tube at a distance above the normal mercury level and project downwards to the required point. This arrangement may provide for local signalling at the barrier between sections, or may give an indication at a distance or produce an automatic record or control of the conditions.

By constructing the U-tube device in the manner indicated it can be made as a completely sealed enclosure consisting of the U-tube with its mercury and its contact wires and the two branches with their porous discs and the chambers enclosing them.

The understanding of the invention will be assisted by the following description of an example in which it is applied to an electric cable containing gas under pressure constructed in accordance with the specification of United States Patent No. 2,067,169.

In this specification reference will be made to the accompanying drawings, wherein,

Figure 1 is a longitudinal section of a complete joint between two lengths of the cable,

Figure 2 is a view, partly in elevation and partly in longitudinal section and on an enlarged scale as compared with Figure 1, of the leak indicating device with which the joint shown in Figure 1 is fitted,

Figure 3 is a view, which is partly an end elevation and partly a section on the line III—III of Figure 2, of the device shown therein,

Figure 4 is a plan of the device shown in Figures 3 and 4 with the dome in which it is housed removed,

Figure 5 is a fragmental section taken on the line V—V of Figure 4 but drawn to a larger scale than Figures 2-4 and

Figure 6 is a circuit diagram of the leak indicating device fitted with a signalling device.

The cable joint shown in Figure 1 is a joint between two lengths 1, 1a of 33 kv. three core, gas filled paper insulated cable of the kind in which the paper tapes are pre-impregnated with a setting compound and the interstices between the tapes are filled with gas—for instance nitrogen—under super-atmospheric pressure. The cable is provided with a double lead sheath, the inner sheath of the lengths 1 and 1a being designated 2 and 2a, and the outer, 3 and 3a, respectively. In this joint, the three core conductors 4 of one length are connected by ferrules 5 to the corresponding conductors 4a of the other length and the conductor joints are individually insulated with hand applied insulation 6 which is covered with conducting tape and tin foil to form a screen which is a continuation of the core screens. The jointed and insulated cores are then enclosed in a copper tube 7 fitted with conical ends, 8 and 8a, by which it is jointed by wiped metal joints to the ends of the inner lead sheaths, 2 and 2a, respectively. This sleeve is enclosed in a two-part brass alloy sleeve 9 which is sealed at its ends to the inner and outer lead sheaths of the cable by cast metal joints, 10 and 10a, and is filled to the level indicated with liquid insulating compound. The anchored ends of the metal tape reinforcement, 11 and 11a, are respectively embedded in the cast metal of the joints 10 and 10a. To the outer ends of the conical moulds, 12 and 12a, for these joints are secured clamps, 13 and 13a, by which the wire armouring of the cable is anchored. The whole is enclosed in a protection box 14 of reinforced concrete. Normally a by-

pass connection is provided between the interior of one cable length and the interior of the other cable length, consisting of pipes, 15 and 15a, sealed into the inner sheaths, 2 and 2a, respectively and respectively leading to domes, 16 and 16a, on top of the outer sleeve 9, and of a pipe 17 leading from the interior of one dome to that of the other. This permits of a free flow of gas between one jointed length and the next.

To apply the invention to the joint described in the proceeding paragraph only minor structural modifications are necessary: One of the two domes, which are normally similar and of the shape shown at 16a, is replaced by a larger dome

15 of the shape shown at 16, in which is housed the leak indicating device which is connected across the ends of the pressure equalising pipes 15 and 17 therein, and the resistance of the joint to flow of gas therethrough is increased by the 20 application of a barrier 18 of insulating tape over the screening of each of the exposed parts of the cores of one cable length and of a barrier 19 of insulating tape over the end of the inner lead sheath of that length and over and in between the barrier tape covered cores emerging therefrom.

The construction of the leak-indicating device housed in the larger dome 16, shown to the left in Figure 1, is shown more clearly in Figures 2, 3 and 4. It comprises a U-tube 20 of glass secured in a clamp 21 mounted on a pillar 22 upstanding from a horizontal baffle plate 23 which separates the interior of the dome 16 from the underlying gas space in the outer sleeve 9 which space is charged up by gas leaking past the screws by which the baffle plate is secured. This U-tube may have a bore of 15 mm. and an overall height of 60 mm. It contains mercury just sufficient to close the bend in the U-tube with a small margin. The upper end of each leg is closed by a dome shaped end wall as is shown most clearly in Figures 3 and 5. A short distance below the upper end of each leg is a short branch tube, 24, 24a. On each of these branch tubes, 24, 24a, is a cylindrical glass chamber 25, 25a, respectively, each of about 30 mm. internal diameter and having across the middle of its length a disc 26 of sintered glass about 2 mm. thick with pores of the order of 50 microns diameter. In the end wall of each chamber 45 adjacent to the U-tube is a short connecting tube 27 adapted to fit in and be sealed to the branch tube. This connecting tube is at the lower side of the chamber so that the surface of its wall at the lowest part forms a clear continuation of the lowest part of the wall of the chamber, thus giving a clear run back for any globules of mercury that may enter the chamber. The branch tube, 24 and 24a, are inclined upwards from the U-tube so as to facilitate this run back from the chambers 25 and 25a, respectively. In the other end walls of these chambers there are short centrally placed tubular pieces, 28 and 28a, respectively. To the tubular piece 28 is sealed the neighboring end of the by-pass pipe 17. The neighboring end of the other by-pass pipe 15 is open to the interior of the dome so that the enclosed space forms the connection between pipe 15 and the open end 28a of the chamber 25a.

In each of the legs of the U-tube is fused a pair of wires, 29 and 30 in one and 29a and 30a in the other. The ends of these wires inside the tube extend downward to about one sixteenth of one inch above the level of the mercury when in the balanced position. The wires 30 and 30a, that is, one of each pair, are connected externally

to the dome 16, which is of metal, and through it to the metal of the joint enclosure 9 and thereby to the external metal parts of the cable itself, thus providing a continuous earthed connection. The other wires, 29 and 29a, of the two pairs are brought out and connected to the cores of a twin-core cable 31 passing through the top of the dome. This cable is preferably a cable having a metal sheath which can be soldered to the dome wall. A compound seal 32 is preferably provided for its lower end. The cable 31 together with the by-pass pipes 33 and 33a for the outer lead sheaths 3 and 3a, respectively, are led out through an opening in the lid of the box 14, the cable terminating in a three-pin socket outlet 34 in an inspection chamber 35 (Figure 6), the metal sheath of the cable being connected to the earth socket of the socket outlet. Into this socket outlet can be plugged a portable device 36 for electrically detecting and indicating a displacement of the mercury in the U-tube. This comprises a battery 37, one terminal of which is connected to the earth pin of the plug 38 and the other of which is connected through a volt meter 39 or the like and a two-way switch 40 to one or other of the other two pins of the plug, depending on the setting of the switch. A displacement of the mercury in the U-tube sufficient to short circuit one pair of wires is, if the switch is appropriately set, indicated by a reading on the instrument 39, the direction of displacement, and hence the direction of flow of gas due to the leak, being indicated by the position of the switch.

With such an arrangement flow of gas through the device at the rate of 0.01 cu. ft. per second can take place continuously for the filling of the cable without the risk of the passage of mercury through either of the porous discs. Under leak detecting conditions the contacts will be closed when there is across the U-tube a pressure difference of $\frac{1}{8}$ inch of mercury which may correspond to a gas leakage of 0.000001 cu. ft. per second.

It will be understood that although Figure 1 of the drawings shows only the jointed end of two cable lengths the system of which these lengths form part will as a rule comprise many lengths and joints and that it will be advantageous to sectionalize the system at, and to apply the invention to, every joint.

What I claim as my invention is:

1. An electric gas-filled cable installation comprising in combination at least two sections of cable containing gas under pressure, a joint between said sections constituting a barrier restricting flow of gas between said sections, a by-pass across said barrier and a pressure relief manometer in said by-pass consisting of a large bore U-tube containing sufficient mercury to close the passage between the limbs thereof and prevent flow of gas through the by-pass when the pressure difference between the gas in said sections is small, as when there is a gas leak in one of said sections, and indicate the existence of said small pressure difference by its displacement and provided with means for preventing carry-over of mercury therefrom into the cable when said pressure difference is sufficiently large to cause the gas to bubble through the mercury as when the installation is being charged with gas.

2. An electric gas-filled cable installation comprising in combination at least two sections of cable containing gas under pressure, a joint between said sections constituting a barrier re-

stricting flow of gas between said sections, a by-pass across said barrier and a pressure relief manometer in said by-pass consisting of a large bore U-tube having limbs with closed ends, an upwardly inclined tubular branch projecting from each limb at a point below the closed end thereof, a chamber on each branch, a gas porous, mercury-resistant barrier in each chamber dividing it into a lower part in communication with the branch carrying the chamber and an upper part, means for connecting the upper parts of said chambers to said by-pass and sufficient mercury in said U-tube to close the passage between the limbs thereof and prevent flow of gas through the by-pass when the pressure difference between the gas in said sections is small, as when there is a gas leak in one of said sections, and indicate the presence of said small pressure difference by its displacement but not so much as to prevent gas from bubbling through said U-tube when the pressure difference between the gas in said sections is large, as when the installation is being charged with gas.

3. In an electric gas-filled cable installation comprising at least two cable lengths, a joint between said lengths which comprises means for jointing each conductor of one cable length to the corresponding conductor of the other cable length, means for insulating the jointed conductors, a tubular enclosure for the jointed and insulated conductors making joint at each end with a gas-impervious sheath of the adjacent cable length, means restricting the flow of gas from at least one of the two jointed cable lengths into said enclosure, a large bore U-tube disposed outside said enclosure, means for placing one limb of said U-tube in gas communication with the interior of one cable length at a point outside said enclosure, means for placing the other limb of said U-tube in gas communication with the interior of the other cable length, sufficient mercury contained in said U-tube to close under normal operating and under leak conditions the passage between the limbs of said U-tube but not so much as to prevent gas from bubbling through said U-tube when the installation is being charged with gas, means for preventing entry of mercury into the interior of the jointed cable lengths when there exists a pressure difference between the cable lengths sufficient to cause gas to bubble through the mercury, and means for indicating a displacement, and the direction of such displacement, from normal of the mercury level due to a small pressure difference between the cable lengths occasioned by a leakage of gas from one cable length.

4. In an electric gas-filled cable installation comprising at least two cable lengths, a joint between said lengths which comprises means for jointing each conductor of one cable length to the corresponding conductor of the other cable length, means for insulating the jointed conductors, a tubular inner enclosure for the jointed and insulated conductors making joint at each end with a gas-impervious sheath of the adjacent cable length, means restricting the flow of gas from at least one of the two cable lengths into said enclosure, an outer enclosure for the inner enclosure also making joint at each end with the said gas-impervious sheath of the adjacent cable length, an opening in the top of said outer enclosure, a baffle plate covering said opening, a large bore U-tube mounted on said baffle plate having limbs with closed ends, a

cover enclosing said U-tube and making a gas-tight joint with the wall of the outer enclosure, an upwardly extending tubular branch in one of the limbs of said U-tube, a tubular connection between said branch and the interior of one cable length, passing through said baffle plate and between said inner and outer enclosures, said connection including a gas-porous, mercury-resistant barrier, an upwardly extending tubular branch in the other of the limbs of said U-tube in communication through a gas-porous mercury-resistant barrier with the interior of said cover, a tubular connection between the interior of said cover and the interior of the other cable length, passing through said baffle plate and between said inner and outer enclosure, sufficient mercury contained in said U-tube to close under normal operating and leak conditions the passage between the limbs thereof but not so much as to prevent gas from bubbling through said U-tube when the installation is being charged with gas, and means for indicating a displacement, and the direction of such displacement, from normal of the mercury level due to a small pressure difference between

the cable lengths occasioned by a leakage of gas from one cable length.

Certificate of Correction

Patent No. 2,520,624

August 29, 1950

EDWARD LESLIE DAVEY

It is hereby certified that error appears in the printed specification of the above numbered patent requiring correction as follows:

Column 1, line 7, for the word "agreement" read *arrangement*; column 3, line 25, for "length" read *lengths*; column 4, line 11, for "proceeding" read *preceding*; column 5, line 46, for "end" read *ends*;

and that the said Letters Patent should be read as corrected above, so that the same may conform to the record of the case in the Patent Office.

Signed and sealed this 14th day of November, A. D. 1950.

[SEAL]

THOMAS F. MURPHY,
Assistant Commissioner of Patents.
